UNITED STATES PATENT OFFICE.

HAROLD L. TUNISON, OF UPPER MONTCLAIR, NEW JERSEY, ASSIGNOR TO FRANK L. DYER, OF MONTCLAIR, NEW JERSEY.

AUTOMATIC STOP MECHANISM FOR TALKING-MACHINES.

1,385,407.

Specification of Letters Patent. Patented July 26, 1921.

Application filed June 17, 1919. Serial No. 304,754.

To all whom it may concern:

Be it known that I, HAROLD L. TUNISON, a citizen of the United States, residing at Upper Montclair, in the county of Essex, State 5 of New Jersey, and have a post-office address at No. 219 Alexander avenue, Upper Montclair, N. J., have invented certain new and useful Improvements in Automatic Stop Mechanism for Talking-Machines, of which 10 the following is a specification.

My invention relates to certain new and useful improvements in automatic stop mechanisms for talking machines, of the type in which the operation of the mechanism is controlled by the position of the tone arm which has a generally diametric movement with respect to the record disk.

My improved automatic stop mechanism is adapted to be assembled as a part of any 20 talking machine having a tone arm or other element partaking of a relatively transverse movement with respect to the record. Since the device is extremely simple and compact, it may also be manufactured and sold as a 25 separate attachment capable of being applied to existing types of talking machines.

My improvements are essentially mechanical and comprise a friction brake which, when released, will engage and prevent rotation of the turn table or other record carrier, said brake being locked in a withdrawn 30 position during the playing of the record, but being tripped or released when the tone arm or other controlling element has reached 35 a predetermined point transversely of the record.

Automatic stop devices of this type, both electrical as well as mechanical, are of course, well known. Such stop devices, as 40 heretofore suggested, have been adjustable to accommodate records of different length; or in other words, have been arranged to operate or trip the brake mechanism at the desired point of the transverse travel of the 45 tone arm regardless of the length of the record. In the case of an electrical device, it is not difficult to set the stylus in the last groove of the record and to therefrom determine when the brake device shall be electrically tripped, whereby when the tone arm 50 reaches a point corresponding with the last groove, a circuit will be closed to thus release the brake and arrest the rotation of the turn table or other record carrier. Electrical devices, while thus sufficiently accu-

rate, are relatively complicated, likely to get out of order, more or less clumsy in appearance, and, of course, they fail to work if any derangement occurs in the electrical circuit or in the battery or in the contacts.

Automatic stop mechanism, as heretofore suggested, of the mechanical type, have been simple in construction, compact in appearance and rugged in operation, but they have lacked accuracy of adjustment. With some 60 mechanical stops the brake has been locked in a withdrawn position by various arrangements of triggers which are adapted to be released by the movement of the tone arm or other element as the same approaches the 70 point relative to the record where the turn table or other record carrier is to be arrested. With the prior mechanical devices with which I am familiar, the arrangement is such that the adjustment point is that at 75 which the tone arm engages the tripping mechanism, and therefore there is necessarily a further movement of the tone arm before the actual tripping takes place. Obviously the adjustment is very delicate because 80 the lateral travel of the stylus is of the order of one one-hundredth of an inch for each rotation of the record, and this lateral travel is, of course, proportionally diminished if the tone arm engages the brake trip 85 at a point intermediate of its pivot and its free end. With these prior mechanical devices, the attempt has been made to so make the adjustment that the brake will be actuated at the instant corresponding with the 90 last groove of the record. This, however, is purely a matter of guess; ordinarily the operator engages the stylus three or four grooves short of the last groove and sets the release mechanism to correspond with the 95 point thus selected; then, as the tone arm nears the completion of the record at the point selected, it will commence to operate the trigger, the expectation being when the record has been completely played and the 100 stylus is in the last groove the brake will be released so as to arrest rotation of the turn table. Obviously this human factor is unreliable; if the mechanism is set to operate too far in from the last groove, the brake 105 will be released and the turn table stopped before the record has been completely played; on the other hand, if not set far enough in from the last groove, the brake mechanism is liable not to operate at all. 110

Furthermore, it is a difficult matter, even at best, to select the proper groove where the adjustment is to be made owing to the minute size of the grooves.

5 So far as I am aware, no one has heretofore suggested a mechanical device by which the brake mechanism may be set to operate with the stylus in the last groove of the record and will operate with certainty and 10 accuracy when the stylus has reached the point at which the adjustment was made. This result I accomplish with my present improvements. To this end, I have designed an improved brake mechanism in which 15 when the stylus is engaged with the last groove of the record (or, of course, any other point where the record is to be stopped) and the brake mechanism is adjusted with respect to the tone arm at that identical 20 point, the adjustment will correspond to the tripping point of the trigger, or, in other words, will correspond to the exact instant where the brake will be released. Having thus determined the tripping point of the 25 brake releasing mechanism, I so coordinate the parts that when the tone arm is moved to the commencement of the record the trigger will be moved automatically into position to receive the brake mechanism and hold it in a 30 withdrawn position. Thereupon, as the tone arm progresses transversely across the face of the record, and as it nears the end of the record, it commences to gradually operate the trigger, which will be finally released at 35 the instant corresponding to the precise point of original adjustment. This capacity of my improved mechanism of automatically bringing the trigger into operative position to engage the brake mechanism provides a 40 very accurate mechanical determination of the movement which the tone arm shall have in tripping the releasing mechanism; or, in other words, I determine mechanically and automatically the extent to which the tone 45 arm shall move in releasing the trigger, whereas, with devices as heretofore proposed, this determination has been a matter of guess work on the part of the operator who engages the stylus a sufficient distance in- 50 ward from the end of the record to provide for the tripping of the trigger, as I have explained. The essential distinction between my improved stop mechanism is that the 55 point of adjustment or determination corresponds to the tripping point of the trigger, which after its adjustment is automatically brought into position to engage and withhold the brake, and the tone arm engages the tripping mechanism before the point of ad- 60 justment is reached and gradually with- draws the trigger which releases the brake at the point of adjustment. With prior de- vices, the point of adjustment has been that 65 point where the tone arm engages the trip and commences to release the trigger, so that

the further movement of the tone arm after passing the point of adjustment acts to release the trigger, which therefore frees the brake at a point that the operator has to guess at as a matter of experience. This 70 general idea of providing for the positioning of mechanism at a point corresponding to the final release of the trigger, and the automatic movement of the trigger thereafter into position to lock the brake withdrawn, 75 may be carried out by a variety of mechanical devices all involving the same inventive thought.

With the preferred embodiment of the invention, I make use of a brake device having a trigger pin arranged to lock the brake in a withdrawn position, said brake being spring actuated, whereby when the trigger pin is tripped the brake will be released to engage and arrest rotation of the turn table 80 or other record carrier. I provide a tripping lever which is adapted to engage and trip the trigger pin when the tone arm has been moved to the predetermined point, and with the preferred form of the device I also 85 use a determining arm to which the tripping lever is pivoted, whereby when the tripping lever and determining arm are simultaneously engaged with the tone arm in its final 90 position corresponding to the last groove of 95 the record, the trigger pin will be in the position where it will release the brake. By frictional means the determining arm will remain in the position of its adjustment thus corresponding to the releasing point of the 100 brake, but the tripping lever being capable of independent movement with respect to the determining arm, when the tone arm is moved to the beginning of the record, will be 105 moved relatively to the determining arm so as to bring the trigger pin in position to engage and lock the brake in its withdrawn position. As the tone arm nears the end of 110 its movement, it will come in contact with the tripping lever and gradually move the same pivotally with respect to the determining arm, and when these two arms are thus brought into line the trigger pin will be released to thus trip the brake. In other 115 words, the distance the tripping lever moves with respect to the determining arm is an exact distance determined automatically by the very engagement of the tripping lever and determining arm simultaneously with the tone arm in its final position. 120

It is not necessary to use a separate tripping lever and determining arm as explained, since it is possible to use only a single arm performing the functions of the two. When such a single arm is used it is 125 first brought into engagement with the tone arm to determine the tripping point, and then when the tone arm is moved to begin playing the record, the combined tripping and determining arm partakes of an inde- 130

pendent auxiliary movement, as a result of which the trigger pin is moved into position to lock the brake.

Both forms of the invention are illustrated 5 in the accompanying drawings forming part of this specification, and in which, Figure 1 is a plan view showing the conventional representation of a talking machine record, sound box and tone arm with my present 10 improvements applied to the same. Fig. 2, an enlarged plan view, partly in section, of my improved stop mechanism. Fig. 3, a sectional view on an enlarged scale on the line 3, 3 of Fig. 1 looking in the direction 15 of the arrows. Fig. 4, a section on the line 4, 4 of Fig. 2 on an enlarged scale. Fig. 5 a plan view, partly in section, of a modified arrangement in which a single arm is used for determining the tripping point and also 20 for tripping the brake, the section being taken on the line 5, 5 of Fig. 6 looking in the direction of the arrows. Fig. 6, an end elevation of Fig. 5 showing in full lines the position of the tone arm and pivoted determining-tripping arm in the tripping position, and in dotted lines the position of the same parts when the tripping-determining arm has moved to cause the trigger pin to be moved to lock the brake in its withdrawn 25 position. Fig. 7, a section on the lines 7, 7 of Fig. 6 in the direction of the arrows, the brake being tripped to stop the turn table. Fig. 8, an elevation, partly in section, corresponding to the dotted line 30 position of Fig. 6. Fig. 9, a longitudinal sectional view corresponding to Fig. 7, the brake being in its withdrawn position, and Fig. 10 a separate detail of the annular toothed lower end of the determining-tripping arm. In all of the above views corresponding parts are represented by the same reference numerals.

Referring first to Fig. 1, the turn table 1 is provided with the usual center pin 2, on 45 which is mounted the record 3. A tone arm 4 carries the sound box 5, having a stylus 6, coöperating with the record groove. With the preferred embodiment of my invention, I use a brake lever 7 pivoted on a small 50 circular plate 8, and having a rubber buffer or shoe 9, adapted to engage the periphery of the turn table 1 when the brake is released to stop the record. The brake lever 7 is actuated when tripped by the usual 55 spring 10. In Fig. 1 the brake lever is shown as being tripped to arrest the rotation of the turn table, and in Fig. 2 the brake lever is illustrated in a withdrawn position. The plate 8 is formed with an up- 60 turned arm 10', into which is mounted a small spring barrel 11. The trigger pin 12 extends through the barrel 11, and a coiled spring 13 normally forces the trigger pin to the position shown in Fig. 4. The trigger pin 12 is provided with a head 14 thereon 65 having a cam-like inner face, as shown. A determining arm 15 is connected with the barrel 11, whereby the barrel acts as a pivot for said lever. A spring washer 16 is interposed, and maintained under tension, between the face of the arm 10' and the cap 17 of the barrel. By reason of the spring washer 16, it will be seen that when the determining arm 15 is moved to any angular position it will remain in that position frictionally. A tripping lever 18 is pivoted near the lower end of the determining arm 15, and is provided with an incline cam 19 adapted to be forced into engagement with the cam surface of the head 14 to thus withdraw the trigger pin 12 to release the brake. 70 When the tripping lever 18 is parallel with the determining arm 15 (see dotted lines Fig. 3) the cam 19 will have withdrawn the trigger pin 12 to release the brake. 75 This corresponds to the tripping position of the brake. In operation, if it is desired to stop the record in the last groove, the tone arm is moved to bring the stylus 6 into the last groove, which can be readily done by 80 simply moving the stylus over the smooth inner portion of the record until the stylus engages and is arrested by the last groove of the record. The determining arm 15 and tripping lever 18 are now moved simultaneously until they engage with the tone arm. 85 When this engagement takes place the trigger pin 12 will be withdrawn. Having thus determined the point where the brake is to be released, the tone arm 4 is now moved 90 toward the beginning of the record and as it moves to the position shown in the full lines in Fig. 3, the tripping lever 18 will be moved with respect to the determining arm by the tension of the spring 13 and the 95 engaging cam surfaces. This permits the trigger pin 12 to move to the locking position shown in Fig. 4. The brake lever 7 may now be moved, causing the finger 20 thereon to engage behind the end of the 100 trigger pin (see Fig. 2) and thus lock the brake withdrawn. The movement of the tripper lever 18 with respect to the determining arm 15 may be limited by a pin 21. The brake being thus locked in its withdrawn 105 position, the turn table will commence to move and the record will be played in the usual way. As the tone arm 4 approaches the end of the record it comes into contact with the tripping lever 18 at 110 the full line position, Fig. 3, and gradually moves the said lever toward the position shown in dotted lines. When the tripping lever has been moved to its original position 115 of adjustment, corresponding to that of the determining arm 15, the cam 19 will have withdrawn the trigger pin entirely to release the brake and permit the same to be applied to thus arrest the turn table. It 120 will be obvious that the extent through 125 130

which the tripper arm 18 moves in thus releasing the brake is determined automatically and is always fixed and certain and also that the release point is always predetermined and exact. In case of wear on the end of the trigger pin, I prefer to employ an adjusting screw 22 by which the initial relationship between the determining arm and tripping lever may be adjusted. By 10 this adjustment, also, the brake may be released at any exact position with respect to the record. For instance, the stylus lever 6 may be engaged with the last groove and the adjusting screw 22 may be regulated to 15 cause the brake to be tripped one or two grooves inward from the last groove. Such an adjustment may be desirable where the inertia of the parts to be arrested is relatively great with respect to the braking effect, and where two or three turns may be 20 required to bring those parts to rest.

In Figs. 5 to 10, inclusive, I illustrate a modified arrangement involving the same inventive thought, but wherein a single lever 25 is used having the double function of tripping the trigger pin as well as determining the point where the release of the brake is to be effected. With this modification, the brake comprises a plunger 23 carrying at 30 its inner end a friction pad made of cork, rubber or similar material. A brake lever 25 pivoted to the plate 26 is provided with a finger 27 entering a groove 28 in the plunger 23, whereby the lever 25 may be 35 moved to the dotted line position shown in Fig. 5 to withdraw the brake plunger. A spring 29 actuates the lever 25 to apply the brake when released. The plate 26 is provided with an upturned portion 30 forming 40 a bearing for the plunger 23 and with a similar portion 31 forming a bearing for a barrel 32. Where the plunger 23 passes through the barrel 32 it is made blade-like in cross section, as shown at 33, so that the 45 plunger may move longitudinally with respect to the barrel like a key in a Yale lock, but rotary movement of the barrel will also rotate the plunger. A spring washer 34 is interposed between the upturned portion 31 50 and a nut 35 to hold the barrel 32 in any angular position to which it may be adjusted. A single determining arm and tripping lever 36 is mounted on the barrel 32 so as to be capable of independent angular 55 movement with respect to the barrel. This arm 36 is formed with an eye 37 encircling the barrel and constituting the pivot of the arm, and it is also provided with a groove 38 in which is located the flattened end of 60 the plunger. The groove 38 is formed between the two teeth 39 and 40 in the eye 37 (see Fig. 10), and the flattened end of the plunger is formed with a notch 41 on its under side, which notch, when the brake 65 plunger is entirely withdrawn, will be

brought into line with the tooth 39, as shown in Fig. 9. With this modified form of the invention, the tone arm is first moved to the position where it is to be arrested corresponding generally with the last record groove, and the arm 36 is then moved, as shown in Fig. 6, into engagement with said tone arm. During this adjustment the brake plunger is in its released position shown in Figs. 5 and 7. Having thus made the desired determination, the tone arm is then moved toward the beginning of the record groove and the turn table is started by moving the brake lever 25 into position shown in dotted lines in Fig. 5. This frees the turn table which thereupon commences to rotate. As long as the flattened portion of the plunger 23 remains in the groove 38, the plunger will not be locked in its withdrawn position, but as soon as the notch 41 comes 80 into line with the tooth 39 the lever 36 will then be free to move by gravity to the position shown in dotted lines Fig. 6. This brings the tooth 39 within the notch 41 and locks the brake plunger withdrawn. At the 85 same time the tooth 40 coming in contact with the shoulder 42 of the barrel 32 (see Fig. 8) limits the independent secondary movement of the arm 36 from its position of original determination. The brake being 90 thus locked in its withdrawn position the stylus is engaged with the record and the latter is played in the usual way. As the tone arm approaches the end of its movement it comes into contact with the arm 36 100 and slowly moves it from the position shown in dotted lines to the full line position of Fig. 6. In this movement the tooth 39 is slowly becoming disengaged from the notch 41, and when entirely disengaged, corresponding to the full line position of Fig. 6, the brake will be released and will thus be impelled into contact with the turn table to arrest rotation thereof. Although it is possible, as explained, to carry out the invention by the use of a single arm performing the double function of first determining the brake releasing point and then moving independently to permit the locking of the 105 brake, I prefer to use two separate arms as 110 shown in Figs. 1 to 4 inclusive, because in this way a somewhat simpler arrangement can be constructed and moreover it becomes possible to readily provide for accurate adjustment to take up any wear by a simple 115 adjusting screw such as 22.

Having now described my invention, what I claim as new therein and desire to secure by Letters Patent is as follows:

1. In a stop mechanism for talking machines, the combination with the tone-arm, of a spring actuated brake, a trigger for locking the brake in its withdrawn position, means whereby the trigger may be released by the tone-arm traversing the record, and 120

means coöperating with the tone-arm for automatically determining the releasing point of said trigger, substantially as set forth.

- 5 2. In a stop mechanism for talking machines, the combination with the tone arm and a spring actuated brake of a trigger for normally locking the brake in its withdrawn position, means actuated by the tone arm
 10 which traverses the record for withdrawing the trigger to release the brake, means coöperating with the tone arm for determining the releasing point of said trigger, and means for automatically moving the trigger
 15 into position to hold the brake withdrawn after its releasing point has been determined, substantially as set forth.

3. In a stop mechanism for talking machines, the combination with the tone arm of
 20 a spring actuated brake, a trigger pin for locking the brake in a withdrawn position, a determining arm coöperating with the tone arm for determining the point at which the trigger pin releases the brake, and a tripping lever carried by the determining arm for releasing the brake when the tripping position is reached, substantially as set forth.

4. In a stop mechanism for talking machines, the combination with the tone arm of a spring actuated brake, a trigger pin for locking the brake in a withdrawn position, a determining arm coöperating with the tone arm for determining the point at
 30 which the trigger pin releases the brake, and a tripping lever carried by the determining arm for releasing the brake when the trip-

ping position is reached, said tripping arm having automatic predetermined movement with respect to the determining arm to provide for the engagement of the trigger pin with the brake, substantially as set forth.

5. In a stop mechanism for talking machines, the combination with the tone arm of a spring actuated brake, a trigger pin for locking the brake in a withdrawn position, a determining arm coöperating with the tone arm for determining the point at which the trigger pin releases the brake, a tripping lever carried by the determining arm for releasing the brake when the tripping position has been reached, and an adjustable stop for regulating the movement of the tripping lever with respect to the determining arm, substantially as set forth.

6. In a stop mechanism for talking machines, the combination with the tone arm, of a spring actuated brake, a barrel with friction means to hold it in any position of rotary adjustment, a trigger pin mounted longitudinally in said barrel for locking the brake withdrawn, a determining arm coöperating with the tone arm, and connected to the barrel for adjusting its rotative position, and a tripping lever pivoted on the arm for withdrawing the trigger pin to release the brake, substantially as set forth.

This specification signed and witnessed this 13th day of June, 1919.
